L. WILLIAMS

FURNACE GRATE

Filed Dec. 20, 1927

UNITED STATES PATENT OFFICE.

LESTER WILLIAMS, OF MARSHALLTOWN, IOWA, ASSIGNOR TO MARSHALLTOWN HEATER COMPANY, OF MARSHALLTOWN, IOWA, A CORPORATION OF IOWA.

FURNACE GRATE.

Application filed December 20, 1927. Serial No. 241,337.

The object of my invention is to provide a furnace grate of simple, durable and inexpensive construction, having a number of parallel grate bars which may be easily and quickly placed in position or removed, and when placed in position have means whereby all of the grate bars will be actuated in unison by a single operating means.

More specifically it is the object of my invention to provide a grate comprising an annular frame formed of cast material and a series of grate bars, and means for operatively connecting all of said grate bars, the grate bars and the connecting means being formed of cast or wrought material to eliminate the use of bolts and nuts which soon become rusted and difficult to remove for replacement.

A further object is to provide in a grate comprising an annular supporting frame and pivotally mounted grate bars, improved means for mounting the grate bars therein.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a horizontal sectional view of a furnace showing my improved grate mounted therein.

Figure 2 is a detail sectional view taken on the line 2—2 of Figure 1.

Figure 3 is a detail sectional view taken on the line 3—3 of Figure 1.

Figure 4 is a detail sectional view taken on the line 4—4 of Figure 1.

Figure 5 is a detail sectional view taken on the line 5—5 of Figure 1.

Figure 6 is a detail sectional view taken on the line 6—6 of Figure 1.

Figure 7 is a detail sectional view taken on the line 7—7 of Figure 1.

Figure 8 is an inverted perspective view of the locking device for one of the grate bars.

The numeral 10 indicates the base of a furnace and 11 the upright walls, which are supported on said base. The base 10 is provided with inwardly projecting flanges 12 on which are supported an annular frame member 13. The said frame member comprises semi-circular sections 14 and 15 secured together by means of bolts 16. The

inner edge of the frame member 13 is preferably provided with an upwardly extending flange 17. The member 15 is supported in the back part of the furnace, while the member 14 is supported in the front part of the furnace, said members being secured to the flanges 12 by means of bolts 18.

One side of the base 10 is provided with an opening 19, which is provided with a door casing 20 having a door opening 21, and a downwardly extending flange 22 at its upper edge. The said flange 22 is provided with a notch 23 for receiving the operating rod of the grate hereinafter described.

Supported within the frame member 13, I have provided preferably three grate bars 24, 25 and 26. The grate bar 26 has at its rear end a pivot member 27 terminating in a head 28, while its forward end is provided with a pivot member 29 designed to be supported in a downwardly extending stirrup 30. The member 27 is pivotally mounted in a recess 31 formed in what I shall term a socket lug 32 formed on the inner edge of the member 15. Said lug 32 is provided with a slot 33 for receiving the head 28, said slot being open at its bottom to permit any ashes that might gather in the slot to pass downwardly through the grate into the ash pit below.

By this arrangement it will be seen that the grate bar 26 may be easily and quickly placed into position by first placing the member 29 within the stirrup 30, after first supporting the grate bar in an inclined position with its rear end inclined upwardly, then moving the bar forwardly causing the member 29 to enter the stirrup 30. The rear end may then be lowered, permitting the head 28 to enter the slot 33 and the member 27 to rest in the recess 31.

The grate bar 25 is located at the side of the frame 15 opposite from the grate bar 26, and has its rear end mounted in a manner similar to the grate bar 26, while its forward end is provided with a long operating rod 36 designed to be supported in the slot 23 and secured in said position by means of a detachable plate 37, which may be secured in position by means of two small bolts 38. The bar 25 is removed by removing the plate 37, then permitting the forward end of the rod 36 to be lowered, after which the rear end of the bar 25 may be elevated to cause

the member 28 to disengage the slot 33. The rear end of each of the bars 25 and 26 is provided with a pair of downwardly extending arms 34 slightly spaced apart and having their lower ends connected by means of a longitudinal pin 35.

The grate bar 24 is mounted between the bars 25 and 26 and has its front end provided with a pivot pin 39 mounted in a downwardly extending stirrup 40, while the rear end of the bar 24 is provided with a pivot pin 41 rotatively supported in a stirrup 42. The front end of the grate bar is designed to rest against the stirrup 40, while the rear end of the grate bar is slightly spaced from the stirrup 42. A key 43 is provided to be supported between the rear end of the grate bar 24 and the stirrup 41 to prevent rearward movement of the said bar. The key 43 comprises a head member 44 having a pair of parallel prongs 45 to form a slot 46 for receiving the pivot member 41. The head 44 is designed to rest on the shoulder 45 extending inwardly from the flange 17. The pivot member 39 is of such length that when the key 43 has been removed and the grate bar 24 is moved rearwardly the pivot pin 39 may be elevated from the stirrup 40, permitting the grate bar to assume an inclined position, after which the bar may be moved forwardly and the pin 41 withdrawn from the stirrup 42.

The rear end of the under surface of the bar 24 is provided with a downwardly extending arm 47 in transverse alignment with the rear ones of the arms 34. The lower end of the arm 47 is provided with a laterally extending pin 48. Supported between the arms 34 is an operating link 49 having each end of its lower edge provided with a notch 50 for receiving the pins 35, while the central portion of the link 49 is provided with an opening 51 for receiving the pin 48. The pin 48 prevents upward movement of the link 49, and thereby retains the pins 35 within the notches 50. The pin 48 may be detached from the link 49 by removing the key 43 and imparting rearward movement to the bar 24, which will cause the arm 47 to be moved rearwardly and the pin 48 to disengage the opening 51, after which the link 49 may be elevated to cause the pin 35 to disengage the notches 50. The said link may then be moved endways and removed from the arm 34.

By this arrangement it will be seen that I have provided a grate comprising an annular frame and a series of grate bars which are pivotally mounted and provided with means for operatively connecting all of said bars, so that the said bars may be operated in unison. The parts are so arranged that the grate bars, with their downwardly projecting arms and pivot pins, may be cast integral, the operating link also

being formed of cast material, as well as the annular frame member, the socket lugs and stirrups being cast integral with said frame members, thereby providing a grate in which the bars may be easily and quickly attached or removed without the use of threaded bolts or screws, any other than the screws 38 for supporting the plate 37, said screws being supported in the front end of the furnace where they may be easily operated upon.

By providing the open slots 33 in the lugs 32, any possibility of the sockets becoming clogged with ashes or the like will be entirely eliminated, as the ashes are worked downwardly through the slots each time the grate bars are rotated. The stirrups 40 and 42 are supported substantially beneath the frame members 13 and have their ends open to permit ashes and the like to work freely from said stirrups.

I claim as my invention:

1. A grate comprising an annular frame, a series of substantially parallel grate bars pivotally mounted in said frame, one of said grate bars having a downwardly projecting arm provided with a laterally projecting pin, the other bars each having a pair of downwardly projecting and slightly spaced arms, the lower ends of said arms being connected with a longitudinal pin, each of said bars with its respective arms and pins being formed integral, an operating link having one edge near each end provided with a notch and its central portion with an opening, said link being designed to have its ends supported between the spaced arms of the second grate bars with the laterally projecting pin of the downwardly projecting arm of the first grate bar supported in its central opening, and means for imparting a rocking movement to one of said grate bars.

2. A grate comprising an annular frame, a series of substantially parallel grate bars pivotally mounted in said frame, one of said grate bars having a downwardly projecting arm provided with a laterally projecting pin, the other bars each having a pair of downwardly projecting and slightly spaced arms, the lower ends of said arms being connected with a longitudinal pin, each of said bars with its respective arms and pins being formed integral, an operating link having one edge near each end provided with a notch and its central portion with an opening, said link being designed to have its end supported between the spaced arms of the second grate bars with the laterally projecting pin of the downwardly projecting arm of the first grate bar supported in its central opening, the first grate bar being slidably mounted to move the laterally projecting pin into and out of the opening of said link, a detachable key for

locking said grate bar against sliding movement with the laterally projecting pin within the opening of said link, and means for imparting a rocking movement to one of 5 said grate bars.

3. A grate comprising an annular frame adapted to support a series of substantially parallel grate bars having their ends provided with pivots terminating in head 10 members, the inner edge of said annular frame having socket lugs for supporting the pivot members of said grate bars, said lugs being provided with slots for receiving the heads of said pivot members.

15 4. A grate comprising an annular frame, a series of grate bars pivotally and detachably mounted therein, one of said grate bars being capable of movement endways, the last 20 said grate bar being provided with a downwardly extending arm and a laterally extending pin, the other ones of said grate bars each being provided with a pair of downwardly extending arms slightly spaced apart and having their lower ends connected with 25 pivot pins, a link having its lower edge provided near each end with a notch for receiving the connecting pins of the downwardly

extending arms of said bars, the central portion of said link being provided with an opening for receiving the laterally extending pin of the first said grate bar. 30

5. A grate comprising an annular frame, a series of grate bars pivotally and detachably mounted therein, one of said grate bars being capable of movement endways, 35 the last said grate bar being provided with a downwardly extending arm and a laterally extending pin, the other ones of said grate bars each being provided with a pair of downwardly extending arms slightly spaced 40 apart and having their lower ends connected with pivot pins, a link having its lower edge provided near each end with a notch for receiving the connecting pins of the downwardly extending arms of said bars, the central portion of said link being provided with an opening for receiving the laterally extending pin of the first said grate bar, and means for locking the last said grate bar 45 against movement endways when the laterally extending pin is within the central opening of said link. 50

Des Moines, Iowa, May 18, 1927.

LESTER WILLIAMS.
